AIR BRUSH

Emerson U. Crumley, Muskegon, Mich.

Application July 13, 1938, Serial No. 218,915

5 Claims. (Cl. 299--88)

The present invention relates to air brushes for applying paint and the like; and its object is, generally, to provide an instrument of this character improved in respects hereinafter appearing; and particularly, to provide such an instrument having improved means for regulating the amount of paint applied thereby and the speed with which it is applied, involving means for regulating the position of the field of the movement of the paint-discharging means, means for relatively regulating the paint-discharging means with the means for spraying the paint on the work, etc.; and to provide improved and simple means whereby such operations of the instrument, and combinations of such operations, may be accurately and easily controlled; and further, to provide improved means for housing and protecting the instrument against injury; and further, to provide improved means for mounting the paint-discharging needle of such an instrument on the means for operating the same.

These and any other objects hereinafter appearing are attained by, and the invention finds preferable embodiment in, the illustrative instrument particularly described in the body of this specification and illustrated by the accompanying drawing, in which:

Figure 1 is a front or upper side view of an air brush or paint distributor, the cover being removed to show interior parts thereof and a portion of the body being broken away;

Figure 2 is a like view of parts thereof shown in another position;

Figure 3 is a left hand side view of the same;

Figure 4 is an upper end view thereof shown partly in transverse section taken on line 4--4 of Figure 1;

Figure 5 is a longitudinal sectional view of the same taken on line 5--5 of Figure 1;

Figure 6 is a transverse sectional view thereof taken on line 6--6 of Figure 1;

Figure 7 is an enlarged detail view of parts of the same.

In the embodiment of my invention illustrated by the drawing an instrument for applying paint and the like and commonly called an air brush or paint distributor is shown having a hollow body 1 provided with a removable cover 2. The liquid paint or the like is held in the container or spoon 3 having a shank portion 4 removably held in adjusted position on the left hand side 5 of the body by a screw 6, the spoon having also at its left hand end the discharge vent 7 through which the paint is carried by the outward movement of the reciprocating needle 8

which is removably mounted on the outer (upper) arm 9 of the lever 10 by bending the needle around said arm as shown in Figure 4. This lever 10 is fulcrumed at 11 medially of the link 12 which is pivotally connected at 13 and 14 respectively with the upper end of the link 15 and the free outer end portion 16 of the rigid elongated tubular member 17 which is pivoted at 18 on the body, i. e., on the portion 19 thereof, for limited turning movement toward the right 10 hand and left hand sides 20 and 5 of the body.

This tubular member 17 is moved to, and held in, adjusted positions by turning the screw 21 threaded therein and having an annular groove 22 journaled in the bar 23 which serves to clamp 15 said screw on the body by turning down the screw 24 which passes through this bar and is threaded in the body's right hand side 20, as best seen in Figure 7.

A pelton wheel 25 journaled at 26 on said end portion 16 of the tubular member 17 has a wrist pin 27 turnable and slideable in the longitudinal slot 28 of the inner (lower) arm 29 of the lever 10 for rocking this lever on its fulcrum 11 and thereby reciprocating the needle 8.

The lower end of the link 15 is pivoted at 30 medially of an operating element, the bar 31, slideable and turnable in the longitudinal slot 32 in the left hand side of the body, and having the handle knob 33. This bar 31 is pivoted at 34 20 on one arm 35 of the bell crank lever 36 fulcrumed at 37 on the body, this lever's other arm 38 engaging on the upper side of the adjustable collar 39 on the stem 40 of a valve 41, having a valve seat 42, for controlling the conduit 43 30 through which and through the flexible tube 44 air passes from an outside pressure source.

This conduit 43 has a branch 45 communicating with said rigid tubular member 17 at its pivotally mounted end 18, so that the air stream passing through this member 17 is vented at its discharge end 46 to strike the buckets 47 of the pelton wheel for rotating the same and thereby reciprocating the needle. The other branch 48 of said conduit 43 communicating with the tube 49 in the hollow body leads to its discharge nozzle 50, adjacent the discharge vent 7 of the spoon 3 and at an angle to the direction in which the paint is carried by the needle 8 therefrom, for spraying the paint on the work.

The needle 8 is slidably guided between the side of the spoon at 7, 51 and the bottom of the kerf indicated at 52 in the head of the screw 53 threaded for adjustment in the arm 54 pivot-

ally mounted on the body by the clamping screw 55 as shown in Figure 4.

The outer (upper) end portion of the arm 9 of lever 10 and the needle carried thereby are protected from injury by the housing 56 removably mounted on the upper end of the body by a screw 57 and having at its side an opening 70 for inserting the needle. The valve 60 in the branch 45 may be turned by its handle 61 to regulate the air stream passing therethrough relatively to that which passes through the other branch passage 48.

It will be seen that, in order to accommodate a needle of desired length and also to adjust the field of its reciprocating movement (i. e. the location of the space between the opposite limits of its said movement) and for the especial purpose of fixing the distance to which the point 58 of the needle is to be extruded from the vent 7 of the spoon, the screw 21 may be turned to swing the tubular member 17 toward the left hand side of the body (as to the position shown in Figure 1) so that the needle's point will be extruded farther out of said vent in each of its operative movements, or that this screw 21 may be turned oppositely to swing said member 17 toward the right hand side of the body (as to the position seen in Figure 2) so that the needle's point will not be extruded so far out of said vent, such movements 30 of the rigid member 17 carrying with it the pelton wheel and the fulcrum 11 of the lever 10 without disturbing their fixed spaced relation on said member's rigid end portion 16; and it will be seen that the valve 60 may be turned by its handle 61 to control the flow of air through the branch 45 and the member 17 for regulating the speed of the pelton wheel's rotation, and also for governing relatively to each other the flow of air through this branch 45 and that through the other branch 48 and the tube 49 for spraying the paint; and also that, the initial adjustments by the screw 21 and valve 60 being made, the operations of the instrument may be effected and regulated by manipulating the bar 31 by its knob handle in the following manner and for the following purposes: By pushing this bar inwardly the bell crank's arm 38 is turned downwardly and the valve stem 40 thereby slid against the pressure of the spring 59 for opening the valve 41 to admit air through the conduit 43 and into its said branches, or for partially unseating this valve for governing the volume of the air flow through said branches and thus regulating the speed of the pelton wheel's rotation and that of the needle's reciprocating movement, and also the force of the spraying air stream; and further, that this same bar 31 may be turned downwardly on its pivot 34 for turning the link 12 (through the link 15) on its pivot 14 downwardly 60 to shift the fulcrum 11 of lever 10 toward the pelton wheel's axis 26 and thus increase the length of the needle's reciprocating movements and consequently the distance to which its point 58 is to be extruded from the spoon's vent, and also to increase the speed at which said lever's arm 9 and the needle carried thereby move in each reciprocating movement of the needle; or this bar 31 may be turned upwardly for effecting opposite results.

70 It is evident that the faster the needle is reciprocated by the pelton wheel (i. e. the greater the number of its reciprocations in a given time) and the farther the point of the needle carrying the paint is extruded from the spoon and into the field of the spraying effect of air issuing from the

nozzle 50, the greater will be the amount of paint applied to the work in the given time, and vice versa.

In practice, the instrument is so held in the hand that the knob 33 may be conveniently manipulated, and the valve handle 61 operated by the other hand.

It will be seen that, the screw 21 having been turned to swing the rigid tubular member 17 to desired adjusted position, the various operative movements and combinations of operative movements above described are under constant control and regulation by the operator who is able to effect the same with great nicety by manipulating the bar 31 and the handle 61 of the valve 15 60 as above described; and that the exactitude of such regulation is due largely to the rigid character of the pivotally mounted member 17 which carries the pelton wheel and the fulcrum 11, and to the positive and unyielding character of the 20 connections between the parts.

The invention being intended to be pointed out in the claims, is not to be limited to or by details of construction and arrangement of the 25 particular embodiment thereof illustrated by the drawing or hereinbefore described or shown.

I claim:

1. In an instrument of the class described for applying paint or the like having a paint container with a reciprocating needle for carrying the paint therefrom and a conduit for air under pressure, a tubular member communicating with the conduit pivotally mounted for movement to adjusted position relatively to the container for shifting the field of the needle's reciprocating movement, a wheel journaled on said member for rotation by the air stream therefrom having a wrist pin, a link turnably mounted on said member, a lever fulcrumed on the link engaging the needle for reciprocating the same and having a 40 longitudinally slotted arm in which the wrist pin engages turnably and slidably for rocking the lever, and means for turning the link to move the fulcrum relatively to the wheel for changing the length of the needle's movement and the 45 speed thereof.

2. In an instrument of the class described for applying paint or the like having a paint container with a reciprocating needle for carrying the paint therefrom and a conduit for air under 50 pressure, a tubular member communicating with the conduit pivotally mounted for movement to adjusted position relatively to the container for shifting the field of the needle's reciprocating movement, a wheel journaled on said member for rotation by the air stream therefrom having a wrist pin, a link turnably mounted on said member, a lever fulcrumed on the link engaging the needle for reciprocating the same and having a longitudinally slotted arm in which the wrist pin 60 engages turnably and slidably for rocking the lever, and means for turning the link to move the fulcrum relatively to the wheel for changing the length of the needle's movement and the speed thereof, said means comprising a manually 65 operated element connected with the link for turning the same.

3. In an instrument of the class described for applying paint or the like having a paint container with a reciprocating needle for carrying the paint therefrom and a conduit for air under pressure with a controlling valve, a tubular member communicating with the conduit pivotally mounted for movement to adjusted position relatively to the container for shifting the field of the

the needle's reciprocating movement, a wheel journalled on said member for rotation by the air stream therefrom, a link turnably mounted on said member, a lever fulcrumed on the link engaging the needle for reciprocating the same and engaging the wheel turnably and slidably for rocking the lever, and a manually operated element operatively related with the link and the valve having a movement for turning the link to move the fulcrum relatively to the wheel for changing the length of the needle's movement and the speed thereof and a movement for controlling the valve.

4. In an instrument of the class described for applying paint or the like having a paint container with a reciprocating needle for carrying the paint therefrom and a conduit for air under pressure with a controlling valve, a tubular member communicating with the conduit pivotally mounted for movement to adjusted position relatively to the container for shifting the field of the needle's reciprocating movement, a wheel journalled on said member for rotation by the air stream therefrom, a link turnably mounted on said member, a lever fulcrumed on the link engaging the needle for reciprocating the same and engaging the wheel turnably and slidably for rocking the lever, and a manually operated element operatively related with the link and the valve having a pivotal movement for turning the

link to move the fulcrum relatively to the wheel for changing the length of the needle's movement and the speed thereof and a longitudinal movement for controlling the valve.

5. In an instrument of the class described for applying paint or the like having a paint container with a reciprocating needle for carrying the paint therefrom and a conduit for air under pressure with a controlling valve, a tubular member communicating with the conduit pivotally mounted for movement to adjusted position relatively to the container for shifting the field of the needle's reciprocating movement, a wheel journalled on said member for rotation by the air stream therefrom, a link turnably mounted on said member, a lever fulcrumed on the link engaging the needle for reciprocating the same and engaging the wheel turnably and slidably for rocking the lever, and a manually operated element operatively related with the link and the valve having a movement for turning the link to move the fulcrum relatively to the wheel for changing the length of the needle's movement and the speed thereof and a movement for controlling the valve, the instrument having also a conduit for air under pressure branching from the first-mentioned conduit and having a manually operated valve for regulating the relative flow of air through the conduits.

EMERSON U. CRUMLEY. 30
